UNITED STATES PATENT OFFICE.

THOMAS K. STONER, OF CHICAGO, ILLINOIS.

MACHINE FOR CLEANING BAGS, FABRICS, OR SIMILAR ARTICLES.

1,146,367.

Specification of Letters Patent.

Patented July 13, 1915.

Application filed September 29, 1913. Serial No. 792,260.

To all whom it may concern:

Be it known that I, THOMAS K. STONER, a citizen of the United States, and a resident of Chicago, in the county of Cook and State 5 of Illinois, have invented certain new and useful Improvements in Machines for Cleaning Bags, Fabrics, or Similar Articles; and I do hereby declare that the following is a full, clear, and exact description thereof, 10 reference being had to the accompanying drawings and to the letters of reference marked thereon, which form a part of this specification.

This invention relates to machines for 15 cleaning bags, fabrics, or similar articles.

It relates particularly to that class of machines having a rotary drum mounted in a casing and provided with openings in the drum and communicating with the interior 20 of the casing for permitting the escape of cement, dust and other foreign particles from the articles to be cleaned, and provided with means for removing the dust or foreign particles from the interior of the casing.

25 The principal object of the invention is to provide a simple, economical, and efficient machine for cleaning bags, fabrics or similar articles.

Other and further objects of the invention 30 will appear from the following description and claims and from an inspection of the accompanying drawings, which are made a part hereof.

The invention consists in the features, 35 combinations, and details of construction herein described and claimed.

In the accompanying drawings, Figure 1 is a view in side elevation of a bag-cleaning machine constructed in accordance with my 40 invention and improvements; Fig. 2, a view in end elevation of the machine shown in Fig. 1; Fig. 3, a top plan view of the machine shown in Figs. 1 and 2, with the upper part of the casing removed to show the 45 interior thereof; Fig. 4, an enlarged detail sectional view taken on line 4 of Fig. 1 and looking in the direction of the arrow; the pivotally mounted beater arms located within the hollow drum being omitted for the sake 50 of clearness of illustration; Fig. 5, a central sectional view in detail, taken on line 5 of Fig. 2; and Fig. 6, a detail view in horizontal section, taken on line 6 of Fig. 5, and showing the construction of the door shown 55 in said Fig. 5.

In constructing a machine for cleaning

bags, fabrics or similar articles in accordance with my invention, I provide a stationary outer casing *a* which is, by preference, of cylindrical form and made in two sections, a lower section *b* and a top removable section *c*. This casing is formed, by preference, of sheet metal, such as galvanized sheet iron, and is provided with a supporting frame which may be of any desired, 60 suitable, ordinary and well known form. The supporting frame shown in the drawings comprises a horizontal main frame having side frame members *d* supported upon legs *e* and suitably braced by means of inclined braces *f*, the upper ends of which are connected with the side or main frame members *d* and the lower ends of which are connected with the lower portions of the legs, as shown in Fig. 1. Inclined supporting frame members or braces *g*, which may be formed of angle-iron, are secured to the main frame by means of connecting arms *h*, the upper ends of the inclined frame members or braces *g* being secured to the 65 lower member *b* of the drum by suitable securing means, and the lower ends being adapted to rest upon a stationary foundation *i*. The braces or frame members *g* at each side of the casing may be connected 70 by means of a brace *k* in the form of an angle-iron having its opposite ends secured to and forming a connection between the frame members *g*, and the frame is rendered 75 still more rigid by means of inclined brace 80 rods *l* secured to the brace *k* and to the members *g*, as shown in Fig. 2.

The stationary casing *a* is, by preference, in the form of an annular drum or casing made in two parts *b* and *c*, as already suggested, the peripheral wall of the casing or drum being formed by preference of sheet metal, such as galvanized iron and being provided with peripheral rims *m* of angle-iron at the opposite end margins of the casing and adapted to give the structure the required degree of rigidity and strength. Secured to the outwardly projecting flange portions of each of the angle-iron rims *m*, is an annular plate or ring *n* which may be 95 formed of sheet metal and which extends inward in the direction of the axial center of the stationary drum or casing, as best shown in Fig. 4, so as to form an inwardly projecting flange or inner rim *o* at each end of 100 the annular stationary drum or casing. The flanges *p* of the angle-iron members *m* are 105 110

rigidly secured to the sheet metal casing by means of rivets, or in any ordinary and well known manner, so that the rims *m* form a rigid support for the rings *n* at the 5 opposite ends of the stationary casing or drum. The bottom member *b* of the drum is supported in the main stationary supporting frame above described, and the top member *c* is supported upon the member *b* 10 to which it is removably secured by means of perforated securing flanges *q* (Fig. 2) upon the lower edges or ends of the member *c* and similar flanges *r* upon the upper ends or edges of the lower casing member *b*, and 15 bolts inserted through the perforations in said securing flanges and secured in position by means of nuts, or by other suitable securing means which may be of any desired or well known form. The annular casing 20 or stationary drum thus formed is so mounted that its axial center is in a horizontal position and transverse to the supporting frame upon which the stationary drum or casing is mounted. The opposite ends of 25 this annular casing or drum are provided with openings the margins of which are defined by the annular inner edges or perimeters *s* of the inwardly projecting rims *o*, as indicated in Fig. 4, so that the drum or casing 30 is practically wide open at both ends with the exception of the peripheral portion inclosed by the inwardly projecting rims *o*.

Mounted on the interior of the stationary annular casing or drum above described is 35 a rotary drum *t* which comprises in its construction a pair of annular rims, each formed, by preference, of a multiplicity of peripheral end sections or segmental pieces *u* and *v* which may be of wood joined together 40 so as to form a rigid annular end rim at each end of the drum, an annular metallic strip or rim member *w* being secured to the inner side of each set of segmental wooden rim members *u*.

45 Peripheral slats, rungs or rods *y* are secured at their opposite ends to the inner annular rim members *u* which form the ends of the rotary drum *t*, each of said slats, rungs or rods being secured at its opposite 50 ends to the annular rim members *u* so as to form the periphery or peripheral rigid framework of the rotary drum and form a connection between the rim members *u* or opposite ends of the drum. The slats or 55 rungs *y* which thus connect the opposite ends of the drum are provided with squared or shouldered end portions *z* which fit snugly into similarly shaped angular apertures 2 in the rim members *u* to which the rods are 60 rigidly secured, and rollers or rungs *3* are rotatably mounted at suitable intervals intermediate the rigidly secured rungs *y* and 65 rotatably supported in the annular end members *u* of the drum, said rollers or rungs 3 being each provided with an end bearing

or trunnion *4* which is rotatably mounted in a suitable socket adapted to permit the rotation of said rungs or rollers. The rollers and rungs *3* and *y* are provided with spaces 5 therebetween, (Fig. 5) and are so arranged 70 as to form the peripheral annular wall of the drum. The openings between the rods or rungs are adapted to permit cement, dust and other foreign substances to pass from the interior of the rotary drum between them 75 and into the spaces 6 between the periphery of the rotary drum *t* and the peripheral wall of the stationary drum or casing *a*. The rotary drum *t* is provided with a series of inwardly extending radial blades, paddles 80 or baffles *7* (see Fig. 5,) which are arranged at suitable intervals around the periphery of the drum in position to form a rigid connection between the end members or rim members *u* and to form shelves or supports 85 upon which the bags or other material to be cleaned are raised during the rotation of the drum, and from which the bags or articles to be cleaned fall or tumble to the bottom of the drum during the rotation of the 90 latter in such a manner as to cause the cement particles and other foreign substances to be dislodged or beaten out.

In order to facilitate the cleaning of the bags or other articles to be operated upon, 95 a series of flails or beater arms *8* are provided and secured to the baffles or to suitable supports at or near the periphery of the drum, as shown in Fig. 5, by means of hinge members *9* upon the baffles and hinge members *10* upon the pivoted or hinged ends of 100 the flails or beater arms. These beater arms or flails may be made of gas pipe or other suitable strong and heavy material and, when employed, should be of sufficient 105 length to enable the swinging ends thereof to fall downward during the upward movement of the portion of the drum or of the baffles to which their pivoted ends are secured (see Fig. 5), so as to strike the bags 110 or articles to be cleaned and cause the cement particles and other foreign substances to be dislodged or beaten out. The annular rim or end members *u* and *v* of the inner rotary drum being rigidly connected by means of 115 the baffles *7* and rigid peripheral drum members or rungs *y*, it will be readily seen the rim members *u* form supports adapted to permit the rotation of the peripheral rotary rungs *3*. A rotary drum is thus provided, the opposite ends of which are closed by means of end plates *11* which may be of 120 sheet metal and which are secured at their annular margins to the relatively heavy or wooden segmental rim members *v*, as best 125 shown in Fig. 4. One of the end walls formed by the metallic plates *11* is provided with a suitable opening for admitting bags or articles to be operated upon, and a door 12, shown in Figs. 5 and 6, is slidably 130

5 mounted in position to enable such opening to be readily opened and closed. This door may be of any desired form and when constructed as shown in the drawings consists of a flat plate or sheet of suitable material slidably mounted between guides or ways 13 and 14 in position to form a closure for the opening 15.

Secured to each rim member *w* and supported by means of said rim member upon the inner side of the relatively heavy and strong wooden member *u*, is a peripheral flange 16, each of which projects outward from the corresponding rim member *u* and *w* on the 10 outside of the inwardly projecting flange *o*, as shown in Fig. 4, and an annular flange member 17 is secured to the inner side of each of the annular flange members 16 and comprises an inclined or tapered rim or 15 inner flange 18 which extends laterally from the annular drum members *u* and *w* and beyond the peripheral rungs *y* and 3 which form the peripheral wall of the rotary drum *t* at an incline away from the ends of the 20 rotary drum and in the direction of the periphery of the outer stationary casing or drum, as shown in Fig. 4, so as to form a peripheral, inclined or tapered flange located on the inside of the inwardly projecting stationary flange or rim *o* of the stationary casing *a*, already described, and outside of the 25 peripheral wall of the rotary drum *t*. The overlapping flanges or sheet metal rims 16, 18 and *o* are thus adapted to permit the rotation of the inner rotary drum, and openings 30 19 between the rim members *o* and 16 and openings 20 between the rim members *o* and 18 and openings 21 between the outer peripheral edges of the rim 18 and the periphery of the stationary casing are adapted to 35 admit air to the interior of the casing *a* and to the interior of the rotary drum. (See Fig. 4.)

The annular end or rim members *u* and *v* 40 of the rotary drum project endwise beyond the opposite ends of the stationary casing, as best shown in Fig. 4, and shafts 22 and 23 extend beneath and endwise beyond the opposite ends of the stationary casing *a* and 45 rotary drum *t* and are mounted in suitable bearings 24 upon the side frame members *d*, each of said shafts being provided with spur pinions 25 having annular rims 26 which form supporting rollers or wheels which are 50 in supporting engagement with the lateral annular rim portions 27 of large segmental spur gears 28 which encircle and are supported by the rim or end members *u* and *v* of the rotary drum and are in toothed engagement 55 with the spur pinions or drum-supporting wheels 25 of the shafts 22 and 23. The segments of the large segmental spur gear or toothed rim 28 are secured to the end rim members *v* of the drum by 60 means of lugs or arms 29 and bolts 30 which

extend through the lugs and are anchored in rim members *v*, the bolts being provided with nuts 31 in threaded engagement therewith. The shafts 22 and 23 and the rims or supporting roller portions of the pinions 25 thus form supports for the drum, adapted to support and enable the drum to be rotated in a position concentric to the outer stationary casing or drum. The driving pinions and shafts and all of the bearings for 70 the shafts are thus located entirely outside of both the rotary drum and the stationary drum-inclosing casing, so as to be free from the dust which is confined within the rotary drum and stationary casing. The annular rim members *u*, *v* and the associated plates 75 11 at each end of the hollow drum, close the ends of the same and constitute in effect, headers for the drum. The annular toothed rims 28 are mounted on and secured to the 80 headers.

By supporting the drum upon the rotary shafts and pinions or rollers 25, the opposite ends of the drum are both readily accessible and the opening or door for admitting 85 the bags or articles to be cleaned is readily accessible in any position in which the drum may happen to be stopped. The ends of the rotary drum are in position to close the otherwise open ends of the stationary casing 90 or drum *a*, and the heads or ends of the rotary drum are thus exposed and are supported on the outside of the ends of the stationary casing so that it is only necessary to have an opening or door in the exposed end wall 95 100 of the rotary drum. The door is adapted to be utilized when in a position below the axial center of the drum and is unobstructed by either the supporting framework or other drum-supporting devices. The entire interior of the drum is also unobstructed by any central shaft or other means for rotatably supporting the drum. The main driving shaft 22 is provided with a belt pulley 32, 105 or other suitable, ordinary and well known 110 means adapted to enable the driving shaft 22 to be connected with a suitable source of power. The belt pulley 32 shown in the drawings is loose on the shaft 22 and is provided with a clutch member 33 adapted to be 115 engaged by a mating clutch member 34, which is connected with the shaft 22 by means of a spline or feather 35 extending longitudinally of the shaft and adapted to hold its clutch member in non-rotatable relation to the shaft and permit the movement of the clutch member 34 into and out of clutching engagement with the clutch member 33. The belt pulley 32 is operatively 120 connected with a suitable source of power, such as a motor 36—which may be in the form of an electric motor or an engine or other source of power—by means of a belt 37 mounted upon the driving wheel or pulley 38 of the motor or power shaft. 125 130

The stationary casing or drum *a* is provided with a depression or trough 39 in its bottom portion, as shown in Figs. 1, 2 and 3, said trough being located below the periphery of the inner rotary drum and communicating with the space 6 between the periphery of the rotary drum and the peripheral wall of the stationary casing or drum *a*. This trough is adapted to receive the cement particles, dust and other foreign substances removed from the bags or other articles to be cleaned as they pass from the drum during the rotation thereof, and a conduit 40, in the form of a pipe of sufficient diameter to permit the passage of dust and foreign particles removed from the articles to be cleaned, is connected with a fan or blower 41 which may be of any desired, ordinary or well known type. The fan shown in the drawings is an ordinary rotary fan having an outer casing which forms an air chamber communicating with the conduit or discharge passage 40 leading from the interior of the stationary casing and having a discharge opening 42 adapted to communicate with or discharge dust particles and other foreign substances into a suitable receptacle which may be of any desired form. The driving shaft 43 of the fan is mounted in suitable bearings 44 and 45 and provided with a belt pulley 46 in fixed relation thereto and operatively connected with a pulley 47 by means of a belt 48, said pulley 47 being fixed to the drive shaft of the motor 36.

In operation, the clutch member 34 is moved into clutching engagement with the clutch member 33, thereby operatively connecting the driving shaft 22 of the device with the motor or source of power, which being set in motion causes the rotation of the driving shaft 22 and the pinions 25 which are fixed thereto. The annular flanges or rim portions 26 of the rollers or pinions 25 on the shaft 23 form supports for the rotary drum, and the rotation of the driving shaft 22 with the pinions 25 which are in toothed engagement with the large gears 28 on the opposite ends of the rotary drum causes the rotation of the drum with its baffles or shelves 7 which are adapted to carry upward the bags or articles resting thereon in the interior of the drum until such bags or articles are raised to a point where they will fall or tumble to the bottom of the drum, so as to cause the dust and foreign particles to be removed from the bags or other articles by the friction and manipulation of the fabric or articles and by the action of the articles upon each other during the rotation of the drum. The flails or beating arms 8 being so arranged that the swinging ends fall upon the bags or articles during the rotation of the drum, it is obvious that the dislodging and removal of the dust and foreign particles from the articles is

facilitated by the beating which the articles receive from the flails or beater arms. The dust, cement, or other foreign particles removed from the bags pass through the interstices 5 between the rotary peripheral rungs or rollers 3 and the non-rotary rungs or rods *y* and into the space 6 between the periphery of the rotary drum and the stationary casing and to the trough 39 from which they are drawn through the conduit 40 with the air which is drawn into and through the rotary drum *t* and stationary casing *a* by the fan, and discharged through the discharge opening 42 of the fan or blower 41.

I claim:—

1. A dust-extracting apparatus, comprising a stationary hollow outer casing having a discharge spout, a hollow drum rotatably mounted within said outer casing and having its peripheral wall provided with a plurality of openings, said drum and casing each being provided with a peripheral annular flange; the flange on the drum extending over the flange on the casing, and said flanges being laterally spaced apart to permit air to pass between them into the space between the peripheral walls of the drum and casing, means associated with said discharge spout acting to induce a current of air through the casing for removing the dust, and means for rotating the drum; said drum being provided with a door.

2. A dust-extracting apparatus, comprising a stationary hollow outer casing having a discharge spout, a hollow drum rotatably mounted within said outer casing and having its peripheral wall provided with a plurality of openings, a baffle plate located within said drum and extending inwardly from the peripheral wall thereof, a beater rigid throughout its length located in said drum and having pivotal connection at one end with said baffle plate, said drum and casing each being provided with a peripheral annular flange; the flange on the drum extending over the flange on the casing, and said flanges being laterally spaced apart to permit air to pass between them into the space between the peripheral walls of the drum and casing, means associated with said discharge spout acting to induce a current of air through the casing for removing the dust, and means for rotating the drum; said drum being provided with a door.

3. A dust-extracting apparatus, comprising a stationary hollow outer casing having a discharge spout, a hollow drum rotatably mounted within said outer casing and having its peripheral wall formed of a plurality of rods having spaces therebetween forming passages opening into the said drum, a plurality of beaters located within said drum, each beater being rigid throughout its length and having pivotal connection at one end with the peripheral

- wall of said drum, said drum and casing each being provided with a peripheral annular flange; the flange on the drum extending over the flange on the casing, and 5 said flanges being laterally spaced apart to permit air to pass between them into the space between the peripheral walls of the drum and the casing, means associated with said discharge spout acting to induce a current of air 10 through the casing for removing the dust, and means for rotating the drum; said drum being provided with a door.
4. A dust-extracting apparatus, comprising a hollow outer casing having a discharge opening, a hollow drum rotatably mounted within said outer casing, said drum being closed at its ends by headers, one of 15 which is provided with a door, said drum having its peripheral wall provided with a plurality of openings, said drum and casing each being provided with a peripheral annular flange; the flange on the drum extending over the flange on the casing, and 20 said flanges being laterally spaced apart to permit air to pass therebetween and enter the space between the peripheral walls of 25 said drum and casing, means associated with said discharge opening acting to induce a current of air through the casing, and means 30 for rotating said drum.
5. A dust-extracting apparatus, comprising a hollow outer casing having a discharge spout, a hollow drum rotatably mounted within said outer casing and having its peripheral wall provided with a plurality of openings, said casing being provided with an annular peripheral flange, said drum 35 being provided with an inner and an outer annular peripheral flange; the flange on the casing extending between the flanges on the drum, said flanges being laterally spaced apart to permit air to pass therebetween into the space between the peripheral walls of the drum and casing; the inner flange on the drum being inclined inwardly toward the peripheral wall of the casing and 40 having its outer edge terminating short of the peripheral wall of said casing, means associated with said discharge spout acting 45 to induce a current of air through said casing, and means for rotating said drum.
6. A dust-extracting apparatus, comprising a hollow outer casing having a discharge 50 spout, a hollow drum rotatably mounted within said outer casing and having its peripheral wall provided with a plurality of openings, said casing being provided with an annular peripheral flange, said drum 55 being provided with an inner and an outer annular peripheral flange; the flange on the casing extending between the flanges on the drum, said flanges being laterally spaced apart to permit air to pass therebetween 60 into the space between the peripheral walls of the drum and casing; the inner flange on the drum being inclined inwardly toward the peripheral wall of the casing and having its outer edge terminating short of 65 the peripheral wall of said casing, means associated with said discharge spout acting to induce a current of air through said casing, and means for rotating said drum.

In testimony, that I claim the foregoing 70 as my invention I affix my signature in the presence of two witnesses, this 23rd day of September A. D. 1913.

THOMAS K. STONER.
